UNITED STATES PATENT OFFICE

139,026

DESIGN FOR A PAIR OF SPECTACLES

Vincent Salierno, Newark, N. J.

Application May 8, 1944, Serial No. 113,518

Term of patent 14 years

(Cl. D57—1)

To all whom it may concern:

Be it known that I, Vincent Salierno, a citizen of the United States, residing in the city of Newark, county of Essex, and State of New Jersey, have invented a new, original, and ornamental Design for a Pair of Spectacles, reference being had to the accompanying drawing, forming part thereof.

In the drawing:

I claim:

The ornamental design for a pair of spectacles, as shown.

VINCENT SALIERNO.
